(57) CLAIM

I claim the ornamental design for a fishing jig, as shown.

DESCRIPTION

FIG. 1 is an inverted left side elevational view of a fishing jig showing the new design;

FIG. 2 is a top plan view thereof;

FIG. 3 is a front elevational view thereof;

FIG. 4 is a right side elevational view thereof;

FIG. 5 is a rear elevational view thereof; and,

FIG. 6 is a bottom plan view thereof.
